UNITED STATES PATENT OFFICE.

ERNEST R. CRUMNER, OF VANCOUVER, BRITISH COLUMBIA, CANADA.

BROOM GUARD.

1,404,277.

Specification of Letters Patent. Patented Jan. 24, 1922.

Application filed August 30, 1920. Serial No. 406,803.

To all whom it may concern:

Be it known that I, ERNEST R. CRUMNER, citizen of the Dominion of Canada, residing at Vancouver, in the Province of British Columbia, Canada, have invented certain new and useful Improvements in Broom Guards, of which the following is a specification.

This invention relates to a broom guard, which is designed to reinforce and support a corn straw broom or the like, holding the straws together to form a more effective sweeping head, and prevent the individual straws separating and breaking.

15 The device is fully described in the following specification, reference being made to the drawings by which it is accompanied, in which:

Fig. 1 is a side elevation of one of the 20 wire side frames of the support.

Fig. 2 is a detail view in the plane of the bend of one of the retaining hooks of this frame.

Fig. 3 is a plan showing the adjacent ends 25 of the two side frames and the manner of connecting them together.

Fig. 4 is a view of the connected guard ready for application to a broom, and

Fig. 5 is a view of the broom showing the 30 application of the guard to it.

Each side frame of this guard is formed of a single length of wire, the ends of which are doubled over in the plane of the broom face, from the middle portions 2, which extend across the width of the broom.

40 The bent ends of 3 extend a short distance beyond the width of the broom at the manufacturers' binding 10, and the ends, which project beyond the width of the broom, are turned at right angles, as at 11, across the thickness of the broom head.

The ends, which are bent over at 3, are upwardly turned toward one another in the face plane, as at 4, and are angularly turned 45 from one another in the same plane for a short distance as at 5, and each extreme end is turned inward to form a hook as at 6, the point of which is directed from the plane of the broom face into the thickness of the head. The end of the hook is cut to an acute angle, as shown in Fig. 2, to enable it to penetrate the straw of the broom at or about the manufacturers' binding 10.

50 The inwardly turned ends 11 of each side frame are, as shown in Fig. 3, connected together by small coil springs 7, so that the

horizontal portions 2 of the side frames are resiliently held together on the faces of the broom when the hooks 6 are pressed into the straw, as shown in Fig. 5, to retain 60 the guard in the desired position on the broom.

The natural resilience of the members 4 of the side frames holding the hooks 6 in engagement is supplemented by a light coiled 65 spring 8 connected between the bends where the portions 5 turn outward from the portions 4.

A tubular sleeve 9 of rubber or fabric is applied to the end loops 3 and the springs 70 7 to prevent the straws of the broom from catching between the coils of the springs.

So constructed, the device forms a simple, easily applied and effective guard for a broom of straw or the like, holding the 75 straws compactly together while permitting them to yield to the sweeping movement.

Having now particularly described my invention, I hereby declare that what I claim as new and desire to be protected in by Letters Patent, is:

1. A broom head, comprising side frames bent from wire to extend across the width of the broom parallel to its lower edge and therefrom upward and inward to adjacent 85 the middle line then outward and upward a short distance to adjacent the manufacturers' binding of the broom head where each end is provided with a sharpened hook to penetrate the straw of the broom, springs between the lower ends of each frame outside the side edges of the broom, springs between the bends of each frame adjacent the upper part, and a sheathing of flexible material shielding the first named springs. 95

2. A broom head, comprising side frames bent from wire, the medial portion of each frame extending across the width of the broom parallel to its lower edge, each end being bent back upon the medial portion in 100 a plane parallel to the broom face and, from adjacent the side edges of the broom, bent upwardly and inwardly one toward the other and thereafter outwardly turned from one another, each end being bent and sharpened as a hook to penetrate the broom head, a spring between the outer ends of each frame, a flexible sheath protecting the springs, and a spring between the upturned 105 parts of each frame.

In testimony whereof I affix my signature.
ERNEST R. CRUMNER.
